SPOOL HOLDER

Bert H. Krafft, Chicago, Ill., assignor, by direct and mesne assignments, to Emery La Katos, Newark, N. J.

Application July 5, 1940, Serial No. 344,063

6 Claims. (Cl. 242—130)

The invention relates to a yarn supporting device, and more particularly to a bobbin holder for knitting machines or the like.

The invention has among its objects the production of a holder of the kind described which is very simple in construction, inexpensive to manufacture, and very durable and efficient in operation.

Another object of the invention is the production of such a holder which will readily receive and firmly hold bobbins of various sizes without necessitating any adjustments.

Another object of the invention is the production of such a holder which may be readily raised or lowered as desired.

Many other objects and advantages of the construction herein shown and described will be obvious to those skilled in the art from the disclosure herein given.

There have been, in the past, numerous holders developed for supporting a yarn bobbin or the like. However, such holders did not readily accommodate bobbins of various sizes and shapes without adjustments, or in numerous cases did not securely and firmly hold the bobbin on the support. In the present construction the bobbin engaging member may be readily formed from a single piece of material and is so shaped that it will engage the bobbin at three distinct points instead of engaging throughout the length of the holder, so that regardless of the size and shape of the bobbin, it will be firmly held in position with no tendency to slip off of the holder. The bobbin engaging member likewise is so constructed that if desired it may be raised or lowered on its supporting element.

To this end my invention consists in the novel construction, arrangement and combination of parts herein shown and described, and more particularly pointed out in the claims.

In the drawing, wherein like reference characters indicate like or corresponding parts:

Fig. 1 is a side elevational view of one embodiment of the present invention, showing the bobbin in dotted lines;

Fig. 2 is a front or end elevational view of the same; and

Fig. 3 is a sectional view taken substantially on the line 3—3 of Fig. 1.

Referring to the drawing, 1 designates a supporting element or member, illustrated in the present instance, as a solid rod of cylindrical cross section, the rod being bent intermediate its ends as shown at 2 to provide a horizontally extending portion 3 and a vertically extending por-

tion 4. The horizontal portion 3 may be secured to the knitting machine or other device by any suitable means, the portion 3 being of the desired length to space the bobbin from the central portion of the machine.

Carried by the vertical portion 4 of the member 1 is a bobbin engaging member designated generally by the numeral 5, the lower end of the member terminating in a U-shaped portion 6. The latter is provided with a pair of aligned apertures 7 through which the vertical portion 4 of the supporting rod 1 extends. Passing through the intermediate part 8 of the U-shaped portion 6 is a screw 9, the latter being threaded through 15 a nut 11 positioned adjacent the inner face of the intermediate part 8. The nut 11 may, if desired, be secured to the member 5, or if material of sufficient thickness is employed the screw 9 may be threaded directly into the member 5. 20 However, as the nut is of approximately the same size as the intermediate part 8, it is prevented by the horizontal legs of the U-shaped portion from rotating, so that as the screw 9 is tightened down, the end thereof will engage the portion 4 of the member 1, securely locking the member 5 to the member 1.

The lower leg 12 of the U-shaped portion extends a substantial distance beyond the supporting rod and is then bent, as shown at 13, upwardly and slightly inwardly toward the portion 30 4. It is then bent, as shown at 14, slightly outwardly, thus providing a concave, upwardly extending arm. It is then bent back upon itself at 15 so that the free end 16 of the member extends downwardly and outwardly, the extreme 35 end being turned inwardly, as shown at 17, so that it will not engage the bobbin and hinder removal thereof. It will be noted that the member 5 engages the bobbin B at three points,—

40 namely, adjacent the bends 13 and 15, as shown at 21 and 22, respectively, and on the opposite side of the bobbin, as shown at 23. Thus the conical bobbin B is securely engaged at three points, and as the member is made of a somewhat flexible material, both of the points 22 and 45 23 may move with respect to the point 21, the member in such a case bending at 13 and 15 and possibly along the upwardly extending portion of the member.

Thus the holder will readily adjust itself to receive bobbins of different sizes and shapes. It might be mentioned that in the past holders of this type have ordinarily engaged the bobbin throughout the length of the holder and its respective arms or legs. Such holders, if designed

for short and wide bobbins, did not firmly and securely hold the narrower and more pointed bobbins. Similarly, if designed for the narrow, more pointed bobbins, they did not as efficiently and firmly support the larger bobbins. There have also been holders of light spring wire, which while capable of receiving different sized bobbins, due to their light construction, did not firmly hold the bobbin and required numerous parts to hold the ends of the numerous wires. As such holders were formed of light wire they were easily distorted out of shape. Due to the three-point engagement in the present invention, the bobbin, regardless of size, is securely and firmly held in position with no tendency to slip off the holder. Likewise, the member 5 may be readily raised or lowered to accommodate bobbins of different lengths by merely backing off the screw 9, moving the member 5 to the proper position and again tightening the screw. As illustrated, the member 5 is preferably made from one piece of relatively heavy material as contrasted with prior constructions, so that it is not easily distorted from its desired shape.

It will be noted from the above description that I have provided a holder of the kind described which is very efficient and durable and which will readily receive and hold bobbins of various sizes and shapes.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the kind described, the combination of a supporting member, a bobbin-supporting-element mounted thereon and comprising a single strip of yieldable material having one end portion thereof bent back upon itself to form a U-shaped portion having aligned openings formed in the legs thereof receiving said supporting member, and means for locking said member in said openings, one of the legs of said U-shaped portions being extended beyond the other and bent transversely thereto, said transverse part of said leg being concave and terminating in an inverted U-shaped portion having a free leg of less length than the concave portion.

2. In a device of the kind described, the combination of a supporting member, a bobbin-supporting-element mounted thereon and comprising a single strip of yieldable material having one end portion thereof bent back upon itself to form a U-shaped portion having aligned openings formed in the leg portions thereof receiving said supporting member, a nut, of approximately the same size, as the intermediate part of said U-shaped portion, positioned adjacent the inner side of said part, and a threaded member passing through said nut and intermediate part engageable with said supporting member to lock the latter and said bobbin-supporting-element to one another, one of the legs of said U-shaped portions being extended beyond the other and bent transversely thereto, said transverse part of said leg terminating in an inverted U-shaped

portion, the leg of said U-shaped portion secured to said supporting member being concave, and the free leg being of less length than said concave leg to form three spaced triangularly arranged bobbin engaging portions.

3. A device of the character described adapted internally to support a bobbin having a generally frusto-conical concave surface comprising a supporting member, a bobbin-supporting-element formed of a substantially flat ribbon-like strip of resilient material mounted upon, and adjustable axially along, said supporting member, said bobbin-supporting-element being bent upon itself to provide a long arm affording spaced chord-like bobbin-engaging-portions at the ends thereof and a diverging short arm having a free end and affording a chord-like bobbin-engaging-portion adjacent said free end and substantially midway between the spaced bobbin-engaging portions on said long arm.

4. A device of the character described adapted internally to support a bobbin having a generally frusto-conical surface including a bobbin-supporting-element formed of a substantially flat ribbon-like strip of resilient material bent upon itself to form a long arm providing spaced chord-like bobbin-engaging-portions at the ends thereof and a diverging short arm having a free end and providing a chord-like bobbin-engaging-portion adjacent said free end and substantially midway between the spaced bobbin-engaging-portions on said long arm, each of said chord-like bobbin-engaging-portions being adapted to subtend an arc upon the frusto-conical surface of said bobbin and to make contact therewith at circumferentially-spaced points.

5. A device of the character described adapted internally to support a bobbin having a generally frusto-conical concave surface comprising a supporting-member, a bobbin-supporting-element, formed of a substantially flat ribbon-like strip of resilient material mounted upon, and adjustable axially along, said supporting member, said bobbin-supporting-element being bent upon itself to provide a long arm affording spaced bobbin-engaging-portions at the ends thereof and a diverging short arm having a free end and affording a bobbin-engaging-portion adjacent said free end and substantially midway between the spaced bobbin-engaging-portions on said long arm, each of said bobbin-engaging-portions being adapted to make contact with the frusto-conical surface of said bobbin at a pair of circumferentially-spaced points lying generally in a single radial plane of said bobbin.

6. A device of the character described adapted internally to support a bobbin having a generally frusto-conical concave surface including a bobbin-supporting-element formed of a substantially flat ribbon-like strip of resilient material bent upon itself to form a long arm providing spaced bobbin-engaging-portions at the ends thereof and a diverging short arm having a free end and providing a bobbin-engaging-portion adjacent said free end and substantially midway between the spaced bobbin-engaging-portions on said long arm, each of said bobbin-engaging-portions being adapted to make contact with the frusto-conical surface of said bobbin at circumferentially-spaced points.
